HEAD LAMP CONSTRUCTION

Clarence A. Michel, Anderson, Ind., assignor to
 General Motors Corporation, Detroit, Mich., a
 corporation of Delaware

Application June 11, 1934, Serial No. 730,013

2 Claims. (Cl. 240—41.5)

This invention relates generally to headlamps of the type commonly employed on motor vehicles and the like and more particularly to improvements in the construction of the lens and the means for securing the lens to the body of the lamp to provide a rain and dust tight joint between the lens and the lamp body.

One of the novel features of this invention consists in the provision of a split molding or clamping ring to secure the lens to the open end of the lamp body, the ends of which overlap and which also has means associated therewith to limit the separation thereof.

Another novel feature is the provision with the usual lens engaging gasket on the lamp of means formed on the lens to improve the seal therewith.

The invention also consists in other details of construction illustrated in the accompanying drawing and the following description of one embodiment in which all such modifications are contemplated as may come within the scope of the appended claims.

In the drawing:

Fig. 1 is a vertical longitudinal section of a lamp assembly with parts in side elevation.

Fig. 2 is an enlarged fragmentary part elevation with parts in section adjacent the ends of the split molding or clamping ring.

Fig. 3 is an enlarged fragmentary perspective view of the internal ends of the split molding or clamping ring.

Fig. 4 is an enlarged fragmentary perspective view of a portion of the lens.

Fig. 5 is an enlarged fragmentary perspective view of a portion of a modified lens.

Referring to the drawing, the lamp body 1 and the reflector 2 therein may, for the greater part, assume any desired shape or form. Adjacent its front end the body is provided with an external annular groove or curved seat 3 for a purpose to be presently described, and with an annular curved seat 4 to receive and position the reflector 2 which is formed with a groove 5 for the packing ring or cork gasket 6. A portion of the groove 5 may be bent outwardly to provide a lug 7 to engage within a notch in the flange of seat 4 to prevent relative rotation between the reflector and the lamp body.

The lens 8 is adapted to be assembled with a split molding or clamping ring 9 which may be contracted to draw the lens tightly against the gasket 6 and secure both the lens and reflector to the lamp body. For this purpose the molding or clamping ring 9 is formed at its inner edge with a reinforcing bead 10 to engage within the

groove 3 of the lamp body and is extended around the periphery of the lens to contact at its outer edge with a curved or angled cam surface on the enlarged rim 11 of the lens. To position the molding or clamping ring circumferentially on the lamp body and position and retain the bead 10 within the groove 3, a tongue 12 may be provided for insertion through an opening in the lamp body during assembly and this tongue may be constituted by a depending portion of a separate spring clip member 13 which is located between the bead 10 and the lens rim 11.

Upon the inner surface of the lens 8 adjacent the periphery is a sharp V-shaped ridge 25 which extends entirely around the lens as shown by Fig. 4. Inside of the V-shaped ridge, and also extending all around the periphery is a row of stiples or small conical raised portions 26. The purpose of the ridge is to bite into and deform the cork gasket and thus form a solid dust proof joint and the purpose of the stiples is well known to be to diffuse the light so that the cork gasket cannot be seen thru the lens. While the preferred form shown in Fig. 4 shows only one row of stiples and one circular ridge, a plurality of ridges and rows of stiples may be used as shown in Fig. 5.

Referring now to the detailed construction of the ends of the split molding or clamping ring 9 and the associated means for contracting this ring and limiting separation of the ends, it will be noted particularly from the showing in Fig. 3, that the end 14 is provided with a portion 15 which is offset inwardly from the normal plane thereof to overlap and fit within the end 16 except at the inner edge where the bead 10 and a portion of the end 14 adjacent the bead are removed. The extreme end of member 14 is left a little wider than the remainder of the offset portion as shown at 17. This part will fit within the bead 10 and prevent the overlapping portion from being distorted toward the center of the rim.

The outer half of the portion 15 has a rectangular opening 18 punched out of the center leaving a fairly thin rim 19 around the sides thereof. The inner half has a raised portion 20 formed by pressing this section further than the offset but in the same direction. The end portion 21 of this section 20 is cut away from the sides and pushed up so that it lies in the same plane as the top of the section.

The end 14, just to the rear of the offset, and end 16 have fastened thereto lugs 22 and 23 by rivets 24. Both of these lugs have a hole for the reception of screw 21, and lug 22 has the

hole threaded so that the screw may be screwed into it. Then since the head of the screw engages the other lug when it is rotated, the two ends will be pulled together.

5. In the assembly of this part of the unit, the offset portion is fed inside of the end 16, lug 23 having been fed thru the opening made by folding up flap 21 and riveted in place. The wider portion 17 is snapped under the bead 10 which 10 brings the hole 18 over lug 22. With this in place the engagement of the lug 22 with the end 28 of the offset and cut out portion prevents the two ends from becoming disengaged unless it is snapped out. The bolt 27 is then inserted and 15 screwed up to the desired position. In this way a part of the offset portion always covers the gap between the two end portions and prevents the dust and rain from getting up into the casing. 20 This particular type of lens structure with the annular ridge and row of stippling may be used in conjunction with any means for supporting the lens upon the front of the casing, such as the door or doorless type as well as with the rim type as shown. 25 It can therefore be seen from the foregoing description that the overlapping of the ends of the clamping ring prevents rain and dust from getting into the casing and the sharp V-shaped ridges on the lens, which press into the cork, 30 prevent the same from getting to the reflector.

I claim:

1. A transversely divided lens mounting ring for a lamp casing having its end portions overlapping comprising an offset end on one extremity which is adapted to slip within the other end, the offset end having both an opening therethrough and a raised surface, an angled lug attached to each end for holding the means for securing the two ends together, the extreme end of the opening in the offset end abutting the lug on the other end when the two ends are separated a short distance to prevent total disengagement, the raised surface covering the last mentioned lug in all normal positions. 5

2. A lamp structure including a casing open at one end, a gasket supported adjacent the opening, a lens, a plurality of different types of projections on the rear face of the lens a part of which is adapted to contact the gasket for sealing and the remainder for light diffracting and concealing purposes, a split rim for supporting 15 the lens on the casing, one end of the rim being offset and fitting within the other, the offset end having both an opening therein and a raised surface adjacent thereto, an angled lug attached to each end for securing the two ends together, the lug on the opposite end having a portion extending through the opening in the offset end and the raised surface extending over the last named lug. 20
